UNITED STATES PATENT OFFICE.

BENJAMIN S. GALLUP, OF HAMMOND, LOUISIANA.

CASEMENT-WINDOW OPERATOR.

1,148,375.

Specification of Letters Patent. Patented July 27, 1915.

Application filed February 10, 1915. Serial No. 7,325.

To all whom it may concern:

Be it known that I, BENJAMIN S. GALLUP, a citizen of the United States, residing at Hammond, in the parish of Tangipahoa and State of Louisiana, have invented new and useful Improvements in Casement-Window Operators, of which the following is a specification.

The invention relates to a window opener, 10 and more particularly to the class of casement window operators.

The primary object of the invention is the provision of a device of this character wherein the casement sash of a window can 15 be readily opened, closed or adjusted from within a room without necessitating the raising or removal of a screen when placed therein, the device being of novel form and construction to permit the locking of the 20 casement sash closed, opened, or in its adjusted position.

Another object of the invention is the provision of a device of this character wherein the casement sash is readily movable without undue exertion on the part of 25 an operator, and which will avoid the necessity of the closing or opening of the sash by the hand as usual, or the manipulation of a screen, that is to say, its removal, or the 30 raising thereof to permit the opening or closing of the casement sash.

A further object of the invention is the provision of a device of this character which is simple in construction, readily and easily 35 operated, thoroughly reliable and efficient in its purpose, and inexpensive in manufacture and installation.

With these and other objects in view, the 40 invention consists in the construction, combination and arrangement of parts as will be hereinafter fully described, illustrated in the accompanying drawings, and pointed out in the claims hereunto appended.

In the drawings: Figure 1 is a fragmentary elevation looking toward the inner side of the window with the device constructed in accordance with the invention applied. Fig. 2 is a sectional view on the line 2—2 of Fig. 1, showing the casement 45 sash closed. Fig. 3 is a similar view, showing the casement sash open. Fig. 4 is an enlarged vertical transverse sectional view through the window casement. Fig. 5 is a fragmentary perspective view of the operating handle.

Similar reference characters indicate corresponding parts throughout the several views in the drawings.

Referring to the drawings in detail, A designates a portion of a window casement, B a portion of the casement sash, and C a window screen, which may be either of the hinged or slidable type, while the casement sash is supported on hinges as usual for the swinging thereof to opened or closed 65 position.

The casement sash operator comprises a base plate 10 which is secured in any suitable manner to the upper face of the sill 11 of the window frame or casement, and is 70 formed with a toothed segment 12, while adapted to be swingingly connected with the said plate 10 are superposed adjustably connected disks 13 and 14, respectively, the same having passed centrally therethrough 75 a pivot 15 which is also passed through a spacer member 16 for separating the lower disk 14 from the plate and engages in the said plate 10, while formed in the disk 13 are arcuately arranged rows of openings 17 80 for receiving adjusting screws 18 which are engaged in the lower disk 14 so that these disks can be adjusted relative to each other. The disk 13 is formed with an extension 19 to which is adjustably connected a throw 85 lever 20, the same being formed with a plurality of elongated slots 21 through a pair of which are passed adjusting screws 22, the same being engaged in the extension 19 for the fastening of the lever 20 thereto, it being readily seen that the lever can be adjusted to vary the throw thereof.

Formed on the disk 14 is a handle extension 23 to which is connected a swinging operating handle 24 by means of a hinge 25. 95 The handle contiguous to the hinged connection 25 is formed with a toothed keeper 26 which is adapted to engage the toothed segment 12 when the handle is swung to lowered position for the locking of the throw lever 20 against movement. Secured to the bottom rail of the casement sash B is a cam plate 27 which is formed with a curvilinear cam slot 28 in which works a pivot bolt 29 mounted in the outer end of the lever 20 for the slidable connection of the latter with the cam plate 27 so that on the raising of the handle 24 for the disengagement of the keeper 26 from the segment 12, and upon moving the said handle 100 105 110

24 in one direction the lever 20 will be operated so as to swing the casement sash B to open position, the swinging movement of the sash being determined by the extent of 5 the slot 28 in the cam plate 27 fastened thereto. Of course it is obvious that on a reverse movement of the handle 24 the sash B can be closed, or on limiting the movement 10 of the handle the sash can be swung to any desired position to vary the opening of the window, and on lowering the handle 24 the keeper 26 will engage with the segment 12 thereby securing the sash in its adjusted 15 position, or either opened or closed according to the adjustment of the said handle by the operator. Secured to the base plate 10 is a covering plate 30 formed with a depending marginal flange 31 formed with an opening 32 in which works the handle extension 23, 20 it being understood of course that the screen frame is cut away at the point of the base plate 10 and covering plate 30 to accommodate the same.

It will be apparent that the window sash 25 when closed or wide open will be locked by the pivot bolt 29 engaging in the offset ends of the cam slot 28 so that it is unnecessary to fasten the same by the handle 24 herein-before described.

30 From the foregoing description, taken in connection with the accompanying drawings, the construction and manner of operation of the device will be clearly understood, and therefore a more extended explanation has been omitted.

35 What is claimed is:—

1. A casement sash operator comprising a

plate adapted to be secured to the sash and having a cam slot provided with reversely directed terminal branches forming seats, a 40 base plate adapted to be secured to the casement and formed with a toothed segment, superimposed adjustably connected disks pivoted centrally in the base plate, a throw arm adjustably connected to one of the said 45 disks, and a pivot bolt mounted in the free end of the arm and movable through the cam slot and adapted to engage either of said seats to hold the sash when opened or closed.

50 2. A casement sash operator comprising a plate adapted to be secured to the sash and having a cam slot provided with reversely directed terminal branches forming seats, a 55 base plate adapted to be secured to the casement and formed with a toothed segment, superimposed adjustably connected disks pivoted centrally in the base plate, a throw arm adjustably connected to one of the said disks, a pivot bolt mounted in the free end 60 of the arm of said seats to hold the sash when opened or closed, a handle swingingly connected to the other disk, and a toothed keeper on the said handle and engageable with the toothed segment to lock the throw arm in adjusted position at points intermediate the extreme movements thereof.

65 In testimony whereof I affix my signature in presence of two witnesses.

BENJAMIN S. GALLUP.
